US0D1065996S

(12) **United States Design Patent** (10) **Patent No.:** **US D1,065,996 S**
(45) **Date of Patent:** **** Mar. 11, 2025**

(54) **FASTENER**

(71) Applicant: **Illinois Tool Works Inc.**, Glenview, IL (US)

(72) Inventor: **Mark Beyer**, Glenview, IL (US)

(73) Assignee: **Illinois Tool Works Inc.**, Glenview, IL (US)

(**) Term: **15 Years**

(21) Appl. No.: **29/845,538**

(22) Filed: **Jul. 8, 2022**

(51) LOC (15) Cl. **08-08**

(52) U.S. Cl.

USPC **D8/395**

(58) **Field of Classification Search**

USPC D8/356, 382, 395; D32/54

CPC . F16B 19/1081; F16B 21/075; B60R 13/0206

See application file for complete search history.

(57) **CLAIM**

The ornamental design for a fastener as shown and described.

DESCRIPTION

FIG. 1 is a side perspective view of a fastener;

FIG. 2 is a front side elevation view thereof;

FIG. 3 is a rear side elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a side perspective view of the fastener joining panels.

The dash-dash broken lines illustrate portions of the fastener that form no part of the claimed design. The dash-dot broken lines define the bounds of the claimed design and form no part thereof.

1 Claim, 8 Drawing Sheets

US D1,065,996 S
